SANDING AND POLISHING MACHINE

Axel Madsen, Sioux City, Iowa, assignor to
 Albertson & Company, Inc., Sioux City, Iowa,
 a corporation of Iowa

Application May 16, 1936, Serial No. 80,031

10 Claims. (Cl. 51—170)

The present invention relates to sanding and polishing machines, and is particularly concerned with improvements in the speed reducing gears and other details of the mechanism.

- 5 In the sanding machines of the prior art, such as those shown in the prior patent of Frans O. Albertson, No. 1,954,977, issued April 17, 1934, when equipped with a sanding disc of the type shown in the patent of Frans O. Albertson and 10 Gustav A. Olsen No. 1,882,693, issued October 18, 1932, difficulties have been encountered in the maintenance of the speed reducing gearing and the armatures of the motors, and many different types of gears have been tested and used. 15 Among these were the worm and worm wheel arrangement shown in the prior patent of F. O. Albertson, mentioned above, and other arrangements.

The principal difficulty is that the motor armatures would break down and become short circuited in some one or more of the many coils contained in the slots of the rotor, due to shock and vibration induced in the armature by the gears and by the action of the sanding disc. 20 It was apparently impossible to secure a long life for the motor driven sanders of that type with the gear arrangements of the prior art, due to this vibration and shock.

One of the objects of the present invention is 25 the provision of an improved sanding machine in which the motor armature is adapted to withstand the ordinary conditions of service to which it is subjected, for a very long period of time.

Another object of the invention is the provision 30 of an improved sanding machine structure in which the shock and vibration usually imposed upon the armature by the speed reducing gears is substantially reduced.

Another object of the invention is the provision 35 of an improved gear structure including a cushioning device which is adapted to transmit power without loss and yet adapted to reduce the vibration, shock and wear which is caused by the transmission of the power through speed reducing gearing.

Another characteristic of the prior art devices 40 without the use of the cushioning device described was that there was an excessive wear on the teeth of the crown gear. The teeth not only wore on the driving side, but on the rear side, and under such conditions the gears in the prior art devices were not capable of withstanding hard conditions of service for as long a period as they should, and it was felt they should 45 stand up longer.

Another object is the provision of an improved 50 speed reducing gearing for sanding and polishing machines which is more durable and more efficient, which eliminates gear tooth vibration, and 55 which may be manufactured at a lower cost than

the speed reducing gearing of the devices of the prior art.

Another object is the provision of an improved cushioning device of the class described which is adapted to withstand the action of grease and other lubricants with which the gear housing is filled, so that the cushioning material will not deteriorate due to the presence of the grease or other lubricant.

Other objects and advantages of the invention 10 will be apparent from the following description and the accompanying drawings, in which similar characters of reference indicate similar parts throughout the several views.

Referring to the drawings,

Fig. 1 is a side elevational view of a sanding machine constructed according to the present invention, with the gear housing broken away, on a plane passing through the axis of the motor shaft, and the gears and other mechanism in 20 the gear housing shown in elevation;

Fig. 2 is an elevational view of a sanding machine constructed according to the present invention, with the motor in elevation and a part of the motor housing and the gear housing shown 25 in section, on the plane of the line 2—2 of Fig. 1;

Fig. 3 is a fragmentary detail sectional view taken on the plane of the line 3—3 of Fig. 1, looking in the direction of the arrows, showing the details of construction of the cushioning device.

Referring to Fig. 1, 10 indicates in its entirety the portable electric sanding machine, which comprises a handle 11, electric switch 12, motor 13, speed reducing gearing 14, and sanding disc 15.

The motor is driven by electric current derived through electrical conductors which enter through the protective rubber hose 16 into the handle 11 and switch box 12. The switch is actuated by the switch lever 17, controlling the electric motor.

The electric motor is of the usual construction, its armature 18 being mounted upon a motor shaft 19, which is rotatably mounted by means of suitable anti-friction bearings 20 located in the socket 21 of the end plate 22.

The speed reducing gearing 14 is contained in a housing 23, which comprises a cast metal member formed with an open lower end 24 in Fig. 1 and another opening 25 at one side for passing the spindle 26.

The housing 23 is secured to the motor end plate 22 by a plurality of screw bolts 27 passing through the housing 23 and threaded into the end plate 22. Gear housing 23 is formed with a bore 28 for receiving the bearing bushing 29 for one end of the spindle 26. The housing wall 30 surrounding the opening 25 is formed with a counterbore 31 for receiving the outer race 32 of an anti-friction bearing, which also comprises the balls 33 and inner race 34.

The outer race 32 is held in its socket 31 by means of a cover plate 35, which has a cylindrical bore 36 and a laterally projecting attaching flange 37. The attaching flange has bores 38 through which the screw bolts 39 pass, which are threaded into the housing 23. The bore 36 in the cover plate has a tightly pressed fit about a sleeve 40, which has an inwardly extending annular shoulder 41 engaging the outer race 32. The sleeve 40 has a counterbore 42, which receives an oil seal comprising a sheet metal housing 43, a leather sealing member 44, and a garter spring 45. Two of the screws which hold the cover plate 35 in place also hold a metal bracket 46, upon which is pivoted, by means of a screw bolt 47, a lever 48, having a pin 49.

The shaft 26 has a cylindrical body 50 and an annular shoulder 51 engaging the crown gear 52, which is located on the reduced cylindrical portion 53. The shaft has a smaller threaded portion 54, which receives the nut 55 that clamps the crown gear against the annular shoulder 51, and the end portion 56 of the shaft is of reduced cylindrical shape and is rotatably mounted in the bearing 29.

Shaft 26 also has an enlarged cylindrical portion 57 for receiving the inner race 34 and a still larger cylindrical portion 58 for engaging the leather sealing member 44 of the oil seal.

The cylindrical portion 59 of the shaft 26 supports a collar 60, which has a pair of radially extending sockets or bores 61, fitting the pin 49.

This collar is secured against rotation by a key 62, and when the lever 48 is pivoted until the pin 49 is in a socket 61 the shaft is secured against rotation. This is convenient when it is desired to attach or remove the sanding disc 15.

The left end of the shaft in Fig. 1 terminates in a threaded portion 63 for receiving the internally threaded hub 64 of the sanding wheel 15. Hub 64 has a sheet metal backing 65, which carries the rubber disc 66. Rubber disc 66 provides a support for a sanding disc 67, which is secured in place by a headed and externally threaded member threaded into the counterbore 68, as shown in my prior Patent 1,882,693, mentioned above.

The housing 23 has an inwardly projecting ledge or flange 69, which has a bearing sleeve 70 pressed into a bore 71. The motor cover plate 22 has a bearing sleeve 72 pressed into a bore 73 and aligned with the bearing 70. A stub shaft 74 is rotatably mounted in these bearings and carries a pinion 76, the teeth of which engage the crown gear 52. Pinion 76 has a tubular hub 77 with an outer cylindrical surface 78.

This cylindrical part is mounted in a cylindrical bore 79 in a gear 80, which meshes with the drive shaft pinion 81. The hub 77 has a plurality of slots 82, preferably equal in number, and equally spaced about its periphery.

The slots 82 carry a plurality of keys 83, which project from the slots into the arcuate slots 84 formed in the wall of the bore 79 of the gear 80. The arcuate slots 84 are much wider than the keys 83 and are adapted to provide space for a cushioning member 85, 86 on both sides of each key 83.

This cushioning member may be made of suitable fiber, such as fabric impregnated with "Bakelite" varnish, or a fiber known as "Taxtrolite", or another known as "Duprene". These fiber blocks 85, 86 are substantially rectangular in shape and have a tight frictional fit in the

arcuate slot 84. When placed in the slot, however, they conform to the shape of the slot, and therefore have curved cylindrical sides and radially projecting edges.

The fiber blocks 85, 86 are preferably made of some material which will withstand the action of grease or gear lubricant without deterioration, and they are made larger than the space provided for them, in order that there may be no backlash. 10

In order to place the fiber blocks in their arcuate sockets, the hub 77 may be provided with apertures 87 for receiving the pins of a wrench. The gear 80 may be grasped by another suitable tool, and all of the blocks 85 on the same side 15 of the keys 83 are first put in place. Then, by the aid of the wrench fittings or tools, the gear 80 and hub 77 are so rotated that the keys 83 compress the blocks 85 tightly, and thus slightly enlarge the space into which the fiber blocks 20 86 are to be inserted. The fiber blocks 86 are then inserted and the pressure on the blocks released. The pinion 76 is then connected to the gear 80 through the resilient cushions 85, 86, which absorb the shock and vibration due to the action of the teeth. 25

It will be noted that these cushions are interposed between the sanding wheel 15 and the motor armature 18, so that the armature is not subjected to the shocks and vibration which might result from the action of the grinding wheel, and it is found that when the present invention is employed no unusual trouble is encountered with the motor armatures. As distinguished from the devices of the prior art, the 35 armatures withstand the use for which they are intended for long periods of time, and the insulation is not broken down; that is, the armature does not become short circuited.

It will thus be observed that I have invented an improved sanding machine having a cushioning means interposed between the sanding disc and the motor armature. My cushioning device is adapted to withstand the action of grease or gear lubricant so that the gear housing may still be 45 filled with the usual lubricant, and the fiber blocks are sufficiently firm so that there is no backlash due to the cushioning device. 40

The blocks have sufficient resiliency, however, under the pressures to which they are subjected, 50 to constitute a resilient cushioning device, and they absorb the shocks and vibration due to the action of the sanding wheel and to the teeth of the gears. When the sanding machine is equipped with this cushioning device, no excessive 55 wear appears on the crown gear teeth, as has been noted in the devices which did not employ such a cushioning device, and the cushioning device also serves to protect the armature from the vibration incident to the contact of the gear teeth. 60

While I have illustrated a preferred embodiment of my invention, many modifications may be made without departing from the spirit of the invention, and I do not wish to be limited to the precise details of construction set forth, but desire to avail myself of all changes within the scope of the appended claims. 65

Having thus described my invention, what I claim as new and desire to secure by Letters Patent of the United States, is:

1. In a sanding machine, the combination of a motor, having an armature and a drive shaft, with a sanding device and a drive pinion for the sanding device, a spindle, speed changing gears 75

between said spindle and said motor drive shaft, and a cushioning device interposed between certain of said gears to absorb the vibration and protect the armature from the effects of destructive vibration.

5. 2. In a sanding machine, the combination of a motor, having an armature and a drive shaft, with a sanding device and a drive pinion for the sanding device, a spindle, speed changing gears between said spindle and said motor drive shaft, and a cushioning device interposed between certain of said gears to absorb the vibration and protect the armature from the effects of destructive vibration, said cushioning device comprising a block of oil resistant fiber compressed between radially extending shoulders, one shoulder being carried by one gear, and the other shoulder being carried by another gear.

3. In a sanding machine, the combination of a motor, having a drive shaft, with a sanding device driven by said shaft, a gear housing for speed reducing gearing, a spindle rotatably mounted in said gear housing, a crown gear on said spindle, and means for driving said crown gear from said motor drive shaft, including a resilient cushioning device whereby the vibration resulting from the teeth of the crown gear are not destructively transmitted to the armature on the motor drive shaft.

30. 4. In a sanding machine, the combination of a motor, having a drive shaft, with a sanding device driven by said shaft, a gear housing for speed reducing gearing, a spindle rotatably mounted in said gear housing, a crown gear on said spindle, and means for driving said crown gear from said motor drive shaft, including a resilient cushioning device whereby the vibration resulting from the teeth of the crown gear is not destructively transmitted to the armature on the motor drive shaft, said means comprising a gear driven from the drive shaft, a pinion for engaging the crown gear, said cushioning device interposing between said latter gear and pinion.

5. In a sanding machine, the combination of a motor, having a drive shaft, with a sanding device driven by said shaft, a gear housing for speed reducing gearing, a spindle rotatably mounted in said gear housing, a crown gear on said spindle, and means for driving said crown gear from said motor drive shaft, including a resilient cushioning device whereby the vibration resulting from the teeth of the crown gear are not destructively transmitted to the armature on the motor drive shaft, said means comprising a gear driven from the drive shaft, a pinion for engaging the crown gear, said cushioning device being interposed between said latter gear and pinion, said cushioning device comprising non-metallic, oil resistant blocks mounted on both sides of a fin carried by said latter pinion.

6. In a sanding machine, the combination of a motor, having a drive shaft, with a sanding device driven by said shaft, a gear housing for speed reducing gearing, a spindle rotatably mounted in said gear housing, a crown gear on said spindle, and means for driving said crown gear from said motor drive shaft, including a resilient cushioning device whereby the vibration resulting from the teeth of the crown gear are not destructively transmitted to the armature on the motor drive shaft, said means comprising a gear driven from the drive shaft, a pinion for engaging the crown gear, said cushioning device being interposed between said latter gear and pinion, said cushioning device comprising non-

metallic, oil resistant blocks mounted on both sides of a fin carried by said latter pinion, and a plurality of other fins and blocks symmetrically located on said latter pinion.

7. In a sanding machine, the combination of a motor with a sanding member driven by said motor and shock resistant gearing interposed between said motor and said sanding member comprising the combination of a supporting shaft with a toothed metal member mounted on said shaft, said toothed metal member having an axially projecting hub, a key carried by said hub in a slot, a second toothed member rotatably mounted on said hub and having an enlarged internal slot providing a space on one side of said key, and an oil resistant fiber block in said space adapted to cushion one toothed member from the other toothed member in the driving action of said members.

8. In a sanding machine, the combination of a motor with a sanding member driven by said motor and shock resistant gearing interposed between said motor and said sanding member comprising the combination of a supporting shaft with a toothed metal member mounted on said shaft, said toothed metal member having an axially projecting hub, a key carried by said hub in a slot, a second toothed member rotatably mounted on said hub and having an enlarged internal slot providing a space on one side of said key, an oil resistant fiber block in said space adapted to cushion one toothed member from the other toothed member in the driving action of said members, said internal slot having a space on the opposite side of said key also, and a second cushioning block arranged in said latter space under initial compression.

9. In a sanding machine, the combination of a motor with a sanding member driven by said motor and shock resistant gearing interposed between said motor and said sanding member comprising the combination of a supporting shaft with a toothed metal member mounted on said shaft, said toothed metal member having an axially projecting hub, a key carried by said hub in a slot, a second toothed member rotatably mounted on said hub and having an enlarged internal slot providing a space on one side of said key, an oil resistant fiber block in said space adapted to cushion one toothed member from the other toothed member in the driving action of said members, said internal slot having a space on the opposite side of said key also, a second cushioning block arranged in said latter space under initial compression, and a plurality of other blocks and keys symmetrically arranged with respect to said toothed members in the same manner.

10. In an abrading machine, the combination of an electric motor having an armature and a drive shaft with an abrading member and a drive shaft for said abrading member, interconnecting drive gears on said two drive shafts whereby the abrading member is driven by the motor, said drive shafts and gears comprising a train of driving elements, and a cushioning device interposed in said train of driving elements and comprising a shoulder carried by one driving element, an opposed shoulder carried by another driving element, and a resilient compressible member between said shoulders, said resilient member being initially compressed whereby the variations in driving torque due to gears or to the effect of the abrading member are absorbed.
